DESIGN FOR A BOWLING ALLEY BENCH

Albert Bersin, Brooklyn, N. Y.

Application October 29, 1940, Serial No. 96,163

Term of patent 7 years

To all whom it may concern:

Be it known that I, Albert Bersin, a citizen of the United States, residing at Brooklyn, in the county of Kings and State of New York, have invented a new, original, and ornamental Design for Bowling Alley Benches, of which the following is a specification, reference being had to the accompanying drawing, forming part thereof.

I claim:

The ornamental design for a bowling alley bench, as shown.

ALBERT BERSIN.
